KNITTING NEEDLE

Ethel W. Burnham, Denver, Colo.

Application June 1, 1936, Serial No. 82,913

13 Claims. (Cl. 66—117)

This invention relates to improvements in knitting needles of both the straight and circular type, employed in knitting flat or tubular articles, by either the Continental or other known methods.

It is the object of this invention to produce a knitting needle that shall be so constructed that it can be used with a crochet action instead of the usual knitting movement, and which therefore enables the knitter to hold the thread in the left hand instead of the right, and thereby eliminate the movement required for throwing the loop over the needle.

Another object is to provide a knitting needle having one end provided on one side with a double pronged hook, one prong of which is employed in the regular knitting operation, while the other is used in purling.

A further object is to provide a knitting band having interchangeable points so that the knitting operation can be reversed by merely interchanging the points, thereby obviating the necessity of reversing the needle in the knitting.

A still further object is to provide a knitting needle having one end terminating in a spherical point which prevents stitches from being accidentally dropped and which also prevents injury to the knitter's finger if pressure is exerted thereon; the other end having a hook similar to a crochet hook.

The above and other objects that may appear are attained by means of a construction and an arrangement of parts that will now be described in detail, reference for this purpose being had to the accompanying drawing in which the needle has been illustrated, and in which

Figure 1 is a view showing the complete needle;

Figure 2 is a view of the left hand end portion of the needle, drawn to an enlarged scale, and partly in section;

Figure 3 is a view similar to that shown in Figure 2, but illustrating the right hand end of the needle;

Figure 4 is a side elevation of the point shown in Figure 3;

Figure 5 is a view, partly in section, showing a modified form of construction;

Figure 6 shows a rigid needle similar to that on the left end in Figure 1;

Figure 7 shows a rigid needle similar to that on the right end in Figure 1; and

Figure 8 is a side view of the hook end of the needle, showing a slight modification.

The needle consists of a band having a central flexible section 5 constructed in a well known

manner from wires coiled about a central flexible core, as shown in Figure 1, or of two straight needles like those shown in Figures 6 and 7.

To each end of the flexible section a solid rigid piece 6 is autogenously connected as by welding, as illustrated in Figure 1, or by a threaded connection as shown in Figure 5. The pieces 6 are of greater diameter than the central section, and are tapered where they connect with the ends of the ends thereof.

At points marked 8 the tapered ends make an angle with the remaining portions of the parts 6 so as to prevent the formation of a sharp bend where they join the center section. A removable tip 9, preferably provided with a spherical point 10, is connected with the left hand end piece 6 of the flexible central section by a threaded connection, as shown in Figure 2. The piece 6 has an axial-threaded opening, and the removable tip 9 is threaded into the shank 11. The joint between piece 6 and the tip 9 must be carefully made so that it will be smooth when the parts are assembled.

The piece 6 attached to the right hand end of the band 5 has a removable tip 12 attached to it by the same kind of a threaded connection shown in Figure 2. The threaded shank 11 of tip 12 is identical with the corresponding shank of tip 9 so that the tips may be interchanged.

The tip 12 terminates in a hook 13 having two prongs 14, whose shape can be clearly seen from Figures 3 and 4, in which the hook has been purposely enlarged relative to the tip for the sake of clearness. The back 15 of the tapered shank of the hook is curved rearwardly so as to extend slightly to the rear of the tip 12 and is then forwardly inclined, forming a tapering head 16 and terminating in the point 17.

The reason for providing the hook with two prongs is that one will always be in proper position for knitting and the other in position for purling, when the latter is accomplished by the method in which the thread and the hooked needle are on top of the other end of the needle.

When it is desired to reverse the knitting the tips 9 and 12 are interchanged, whereby the direction of the knitting can proceed in the opposite direction. If a needle having dissimilar ends is not provided with interchangeable tips, the knitting can only be reversed by reversing the needle in the knitting, which involves a considerable amount of labor and often results in dropping stitches.

The spherical point 10 guards against the accidental dropping of stitches and saves the index finger of the right hand from injury if it is used

to push against the left hand end of the needle, as is sometimes done. It is possible to employ the needle with the spherical point 10 absent and the hook provided as shown.

5 The spherical point can also be used in the absence of the hook, or with a single hook, which modifications are contemplated.

10 The use of a hook of the crochet needle type simplifies the knitting operation for reasons already pointed out, and when a double pronged hook is used, the same advantage is had when purling by the method in which the thread and the right hand end of the needle are positioned on top of the left hand end.

15 The interchangeability of tips of different shape makes it easy to reverse the knitting, as it requires only the interchanging of the tips.

20 The tip 9 tapers outwardly from the joint and is several sizes smaller than the hook end, so as to facilitate the movement of the needle in the knitting, as it will feed faster and easier by such a construction.

25 Instead of securing rigid pieces 6 to the ends of the band and then removably securing the tips 9 and 12 to the end pieces a construction like that shown in Figure 5 can be employed. In this construction the piece 6 and tip 9 are combined so as to form a single rigid needle 6a and the piece 6 and hooked tip 12 are similarly combined.

30 When the construction shown in Figure 5 is used one end of the needle 6a is provided with a threaded socket for the reception of the threaded end 11a of the flexible band 5.

35 When the tips are to be interchanged to reverse the knitting they are unscrewed and interchanged as explained in connection with tips 9 and 12.

40 It is, of course, possible to embody this invention with ordinary rigid needles, as shown in Figures 6 and 7. The parts designated as 6b are similar to that designated as 6a in Figure 5, and may even have the threaded socket. The removable tips 9 and 12 are identical with those shown in Figure 1. The method of operation remains the same.

45 When tubular garments are knitted, a band type needle is used, but when articles like scarfs are knitted, straight needles must be used, in which case the tips are interchanged at each course.

50 It is to be understood that in some instances a single hook may be employed instead of a double hook, as indicated at 18 in Figure 8.

55 Having described the invention, what is claimed as new is:—

1. A pair of knitting needles, one of which has its working end provided with a spherical tip and the other needle having a two pronged hook, cooperative with the spherical tip.

5 2. A pair of knitting needles, one of which has a tapered end portion removably attached thereto, and the other of which has a removable end portion whose tip is formed into a two pronged hook.

10 3. A pair of knitting needles having one end provided with threaded sockets and the other ends terminating, one in a spherical point and the other in a hook.

15 4. A knitting needle having a central flexible portion and rigid ends provided with unlike interchangeable tips, one of which terminates in a spherical enlargement.

20 5. A knitting needle having a central flexible portion and rigid ends provided with unlike interchangeable tips, one of which terminates in a hook, and the other in a spherical enlargement.

25 6. A knitting needle having a central flexible portion and rigid ends provided with unlike interchangeable tips, one of which terminates in a double pronged hook.

30 7. A knitting needle having a central flexible portion and rigid ends provided with unlike interchangeable tips, one of which terminates in a double pronged hook, and the other in a spherical enlargement.

35 8. A pair of cooperating knitting needles, one of which has a tapered knitting end-portion terminating in a ball-tip, and the knitting end of the other needle having a hook.

40 9. A knitting needle having rigid extremities and a flexible connection therebetween, a ball-tip on one extremity, and a hook-tip on the other extremity.

45 10. A knitting needle having rigid extremities and a flexible connection therebetween, and a two-prong hook-tip on one of the extremities, the prongs being on the same side of the extremity.

50 11. A knitting needle comprising a rigid shank, and a two-pronged pointed tip on an end of the shank, the prongs being on the same side of the shank.

12. In knitting equipment, a two-pronged hook for the knitting end of a needle, the prongs being on the same side of the hook.

55 13. As a new article of manufacture, a knitting needle having a two-pronged hook, the prongs being on the same side of the needle.
